Patented Jan. 23, 1973

226,072

TAB OPENER FOR A CONTAINER

William T. Saunders, Weirton, W. Va., assignor to National Steel Corporation

Filed June 29, 1971, Ser. No. 158,142

Term of patent 14 years

Int. Cl. D9—07

U.S. Cl. D9—256

FIG. 1

FIG. 2

FIG. 3

FIG. 4

FIG. 1 is a top plan view of the tab opener for a container showing my new design;

FIG. 2 is a bottom plan view;

FIG. 3 is a side elevational view; and

FIG. 4 is a front elevational view thereof.

I claim:

The ornamental design for a tab opener for a container, substantially as shown.
